RECEPTACLE

Jerome J. Hamlin, South Haven, Mich., assignor
to Herbert Wilkinson, South Haven, Mich.

Application November 20, 1940, Serial No. 366,345

9 Claims. (Cl. 217—40)

This invention relates to improvements in receptacles.

Fruits and vegetables are now quite largely shipped in baskets and these, particularly the larger sizes such as bushel and half-bushel, are commonly round in horizontal dimensions. The result is that much space is lost in transportation and storage as compared to the transportation and storage of such products in rectangular receptacles.

The main objects of this invention are:

First, to provide a receptacle or container which is well adapted for use in the handling of fruits and vegetables, including the packing, storage, and shipment thereof.

Second, to provide a structure in which the wall panels may be formed of fibrous material such as cellular board or container board, at the same time they are supported so that they are not likely to be ruptured or damaged in the use

5 retaining members, the springable character thereof being indicated by dotted lines.

Fig. 7 is an enlarged perspective view of one of the closure end members.

Fig. 8 is a fragmentary section showing further details of the relation of the wall panels to the frame.

Fig. 9 is a plan view of a preferred form of side wall unit in its extended position.

Fig. 10 is an enlarged fragmentary view illustrating a modified form of frame, the modification being particularly in the joining of the parts.

Fig. 11 is a fragmentary plan view showing another joint for the frame parts.

10 Referring to the accompanying drawings, I provide a frame formed of suitable wood stock and comprising corner members 1 and side pieces 2, 2, 3, 3, 4, 4 and 5 extending between and suitably joined to the corner members as by means of dowels or tenons indicated at 6 in Fig. 4. It will be understood, however, that the pieces constituting the frame may be joined by means of dove-tailed tenons 7 and mortices 8, as shown in Fig.

15 10, or by means of fastener members 9 as shown in Fig. 11. It is to be noted that the members 4, 4 and 5 are intermediate the members 2, 2, and 3, 3, respectively, and the number of the intermediate members may be as desired. However, the structure illustrated is sufficiently strong and

20 25 30 35 40 45 50

Referring to the accompanying drawings, I provide a frame formed of suitable wood stock and comprising corner members 1 and side pieces 2, 2, 3, 3, 4, 4 and 5 extending between and suitably joined to the corner members as by means of dowels or tenons indicated at 6 in Fig. 4. It will be understood, however, that the pieces constituting the frame may be joined by means of dove-tailed tenons 7 and mortices 8, as shown in Fig. 10, or by means of fastener members 9 as shown in Fig. 11. It is to be noted that the members 4, 4 and 5 are intermediate the members 2, 2, and 3, 3, respectively, and the number of the intermediate members may be as desired. However, the structure illustrated is sufficiently strong and rigid for ordinary purposes. It will be appreciated that the number of crosspieces and the weight of material would be gauged by the size of the receptacle.

The crosspieces 2, 2 are arranged substantially flush with the ends of the corner members while the crosspieces 3, 3 are arranged in a spaced relation to the ends of the corner members providing recesses receiving end closure members designated generally by the numeral 10. These end closure members comprise crosspieces 11 and slats 12.

The crosspieces 11 of the end closure members have longitudinal grooves 13 therein while the corner members have grooves 14 in their ends aligned with the grooves 13, and grooves 15 in their sides aligned with these grooves 13 and 14.

It will be noted by a reference to the drawings that the closure members fit within the uprights and rest upon the frame side pieces 3. The structure illustrated is provided with a closure at each end.

The closure members are detachably retained by means of the bail-like retaining members 16, the bights of which are arranged in the grooves

of the receptacle.

Third, to provide an improved structure and means for securing the end portions of the receptacle, greatly facilitating the attachment and releasing thereof and permitting effective packing of the contents.

Fourth, to provide a structure having these advantages which is quite economical and at the same time strong and rigid.

Fifth, to provide a structure in which the wall panels may be renewed should they become soiled or damaged.

Objects relating to details and economies of the invention will appear from the description to follow. The invention is defined and pointed out in the claims.

Preferred embodiments of the invention are illustrated in the accompanying drawings, in which:

Fig. 1 is a perspective view of a structure embodying the features of my invention.

Fig. 2 is an enlarged fragmentary section mainly in vertical section on line 2—2 of Fig. 3.

Fig. 3 is a top plan view, parts being partially broken away to more fully show the structure.

Fig. 4 is an enlarged fragmentary view in section on line 4—4 of Fig. 3 showing the end closure retaining member in engaged position by full lines and illustrating by dotted lines a step in the engagement and disengagement thereof.

Fig. 5 is an enlarged fragmentary view illustrating one of the end members partially released and tilted for providing access to the contents.

Fig. 6 is a side view of one of the end closure

55

13 in the members 11 and in the aligned grooves 14 in the ends of the crosspieces with their arms 17 in the grooves 15 in the sides of the side members. The arms 17 terminate in inwardly projecting lugs 18 engaging holes 19 in the uprights, and when the lugs are so engaged, the end members are very securely retained and capable of withstanding such load as may be imposed upon them when the receptacle is filled or in the handling of the receptacles.

These end closure retaining members are formed of spring wire stock so that they may be sprung outwardly as indicated in Fig. 4 for engagement and disengagement and when engaged are effectively retained.

In the embodiment illustrated, the side wall panels 20, 20 and 21, 21 are preferably formed as a unit and of fibrous material such, for example, as cellular board. These wall panels are disposed in alignment and flexibly connected by scorings as indicated at 22.

It will be noted that the wall panels 20 are of somewhat greater vertical width than the panels 21 so that when the unit is placed within the supporting frame the edge portions 23 of the panels 20 overlap or are in lapping supporting relation to the frame members 2. Owing to the inset of the frame members 3, the edges 24 of the panels 21 overlap or are in lapping supporting relation to the members 3.

The end wall panels 25 are arranged in supported relation to the end closure members—that is, they are arranged on the inner side thereof and they are disposed within the side wall panels so that their edges are in supported engagement therewith—that is, they hold the side walls extended.

The receptacle is well adapted for the packing of fruits and vegetables and in packing one end closure member may be applied and if desired the corresponding end panel 25 inserted. The facing of fruit or other product packed may then be arranged, the receptacle filled, and the other end panel and end closure member applied. The receptacle may then be inverted when it is desired to expose the faced contents, the end panel at the face side of course being then removed. This may be very conveniently done owing to the ease with which the end closure members are secured or released.

The wall panels are effectively supported and protected by this frame. It will be understood that it is not necessary to use the end panels 25 unless that is desired, and for certain contents the wall panels should have ventilating holes as 26 therein.

The side slats of the end receptacles are spaced from the members 2 so as to receive the edges 23 of the wall panels 20 and this further serves as a supporting means therefor.

I have illustrated and described my improvements in embodiments which I consider very practical. I have not attempted to illustrate or describe other embodiments or adaptations as it is believed that this disclosure will enable those skilled in the art to embody or adapt my improvements as may be desired.

Having thus described my invention, what I claim as new and desire to secure by Letters Patent is:

1. In a receptacle, the combination of a frame comprising corner members and side pieces extending between and fixedly secured to said corner members, the side pieces of one opposed pair

of side walls being disposed substantially flush with the ends of the corner members and the side pieces of the other pair of opposed side walls being disposed in substantially spaced relation to the ends of the corner members providing end closure member receiving recesses, end closure members comprising cross-pieces and slats extending therebetween, said cross-pieces being adapted to be received within said recesses and having longitudinal grooves in their outer faces, the corner members having grooves in their ends and their outer sides aligned with the grooves of said end closure crosspieces, bail-like end closure retaining members of springable material disposed with their bight ends in said grooves in said end closure crosspieces and engaging the grooves of the ends of the corner members and with their arms engaging the grooves in the sides of the corner members, the arms of said retaining members having inturned lugs engageable in holes in said corner members, the arms being springable to release the retaining members, a wall unit of fibrous material disposed within said frame and comprising aligned flexibly connected wall panels, one opposed pair of said wall panels being in lapping supported relation to the inner sides of the frame side pieces disposed flush with the ends of the corner members and the other opposed pair of wall panels being in lapping supported relation with the inset frame side pieces, the outer slats of the end closure members being spaced from adjacent side pieces to receive the wall panels between them, and an end panel of fibrous material arranged within said side wall panels in supported relation to one of the end closure members and with its edges in supporting relation to the side wall panels.

2. In a receptacle, the combination of a frame comprising corner members and side pieces extending between and fixedly secured to said corner members, the side pieces of one opposed pair of side panels being disposed substantially flush with the ends of the corner members and the side pieces of the other pair of opposed side walls being disposed in substantially spaced relation to the ends of the corner members providing end closure member receiving recesses, end closure members comprising crosspieces and slats extending therebetween, said crosspieces being adapted to be received within said recesses and having longitudinal grooves in their ends and their outer sides aligned with the grooves of said end closure crosspieces, bail-like end closure retaining members of springable material disposed with their bight ends in said grooves in said end closure crosspieces and engaging the grooves of the ends of the corner members and with their arms engaging the grooves in the sides of the corner members, the arms of said retaining members having inturned lugs engageable in holes in said corner members, the arms being springable to release the retaining members, and a wall unit of fibrous material disposed within said frame and comprising aligned flexibly connected wall panels, one opposed pair of said wall panels being in lapping supported relation to the inner sides of the frame side pieces disposed flush with the ends of the corner members and the other opposed pair of wall panels being in lapping supported relation with the inset frame side pieces, the outer slats of the end closure members being spaced from adjacent side pieces to receive the wall panels between them.

3. In a receptacle, the combination of a frame

comprising corner members and side pieces extending between and fixedly secured to said corner members, the side pieces of one opposed pair of side walls being disposed substantially flush with the ends of the corner members and the side pieces of the other pair of opposed side walls being disposed in substantially spaced relation to the ends of the corner members providing end closure member receiving recesses, end closure members comprising crosspieces and slats extending therebetween, said crosspieces being adapted to be received within said recesses and having longitudinal grooves in their outer faces, the corner members having grooves in their ends and their outer sides aligned with the grooves of said end closure crosspieces, and bail-like end closure retaining members of springable material disposed with their bight ends in said grooves in said end closure crosspieces and engaging the grooves of the ends of the corner members and with their arms engaging the grooves in the sides of the corner members, the arms of said retaining members having inturned lugs engageable in holes in said corner members, the arms being springable to release the retaining members.

4. In a receptacle, the combination of a frame comprising corner members and side pieces extending between and fixedly secured to said corner members, the side pieces of one opposed pair of side walls being disposed substantially flush with the ends of the corner members and the side pieces of the other pair of opposed side walls being disposed in substantially spaced relation to the ends of the corner members providing end closure member receiving recesses, end closure members comprising crosspieces and slats extending therebetween, said crosspieces being adapted to be received within said recesses, end closure retaining members engaging said end closure crosspieces and releasably engageable with said corner members, a wall unit of fibrous material disposed within said frame and comprising aligned flexibly connected wall panels, one opposed pair of said wall panels being in lapping supported relation to the inner sides of the frame side pieces disposed flush with the ends of the corner members and the other opposed pair of wall panels being in lapping supported relation with the inset frame side pieces, the outer slats of the end closure members being spaced from adjacent side pieces to receive the wall panels between them, and an end panel of fibrous material arranged within said side wall panels in supported relation to one of the end closure members and with its edges in supporting relation to the side wall panels.

5. In a receptacle, the combination of a frame comprising corner members and side pieces extending between and fixedly secured to said corner members, the side pieces of one opposed pair of side walls being disposed substantially flush with the ends of the corner members and the side pieces of the other pair of opposed side walls being disposed in substantially spaced relation to the ends of the corner members providing end closure member receiving recesses, end closure members comprising crosspieces adapted to be received within said recesses and having longitudinal grooves in their outer faces, the corner members having grooves in their ends aligned with the grooves of said end closure crosspieces, bail-like end closure retaining members of springable material disposed with their bight ends in said grooves in said end closure crosspieces and engaging the grooves of the ends of the corner

members, the arms of said retaining members having inturned lugs engageable in holes in said corner members, the arms being springable to release the retaining members, wall panels, one opposed pair of said wall panels being in lapping supported relation to the inner sides of the frame side pieces disposed flush with the ends of the corner members and the other opposed pair of wall panels being in lapping supported relation with the inset frame side pieces, the outer slats of the end closure members being spaced from adjacent side pieces to receive the wall panels between them, and an end panel arranged within said side wall panels in supported relation to one of the end closure members and with its edges in supporting relation to the side wall panels.

6. In a receptacle, the combination of a frame comprising corner members and side pieces extending between and fixedly secured to said corner members the side pieces of one opposed pair of side walls being disposed substantially flush with the ends of the corner members and the side pieces of the other pair of opposed side walls being disposed in substantially spaced relation to the ends of the corner members providing end closure member receiving recesses, end closure members comprising crosspieces adapted to be received within said recesses and having longitudinal grooves in their ends aligned with the grooves of said end closure crosspieces, bail-like end closure retaining members of springable material disposed with their bight ends in said grooves in said end closure crosspieces and engaging the grooves of the ends of the corner members, the arms of said retaining members having inturned lugs engageable in holes in said corner members, the arms being springable to release the retaining members, and wall panels, one opposed pair of said wall panels being in lapping supported relation to the inner sides of the frame side pieces disposed flush with the ends of the corner members and the other opposed pair of wall panels being in lapping supported relation with the inset frame side pieces, the outer slats of the end closure members being spaced from adjacent side pieces to receive the wall panels between them.

7. In a receptacle, the combination of a frame comprising corner members and side pieces extending between and fixedly secured to said corner members, the side pieces of one opposed pair of side walls being disposed substantially flush with the ends of the corner members and the side pieces of the other pair of opposed side walls being disposed in substantially spaced relation to the ends of the corner members providing end closure member receiving recesses, end closure members comprising crosspieces adapted to be received within said recesses and having longitudinal grooves in their outer faces, the corner members having grooves in their ends aligned with the grooves of said end closure crosspieces, and bail-like end closure retaining members of springable material disposed with their bight ends in said grooves in said end closure crosspieces and engaging the grooves of the ends of the corner members, the arms of said retaining members having inturned lugs engageable in holes in said corner members, the arms being springable to release the retaining members.

8. In a receptacle, the combination of a frame comprising corner members and side pieces extending between the corner members, one opposed pair of side pieces being disposed in spaced

relation to the ends of the corner members providing a closure receiving recess between them, an end closure member comprising end crosspieces adapted to be received within said recesses and having longitudinal grooves in their outer faces, the corner members having grooves at their ends and their outer sides aligned with said grooves in said end closure crosspieces, and bail-like end closure retaining members of springable material disposed with their bights in said grooves in said end closure crosspieces and engaging the grooves at the ends of the corner members and with their arms engaging the grooves in the sides of the corner members, the arms of the retaining members having inturned lugs engageable in holes in said corner members, and the arms being springable to release the retaining members.

9. In a receptacle, the combination of a frame comprising corner members and side pieces extending between the corner members, one opposed pair of side pieces being disposed in spaced relation to the ends of the corner members providing a closure receiving recess between them, an end closure member comprising end crosspieces adapted to be received within said recesses and having longitudinal grooves in their outer faces, the corner members having grooves at their ends, and bail-like end closure retaining members of springable material disposed with their bights in said grooves in said end closure crosspieces and engaging the grooves at the ends of the corner members, the arms of the retaining members having inturned lugs engageable in holes in said corner members.
10. In a receptacle, the combination of a frame comprising corner members and side pieces extending between the corner members, one opposed pair of side pieces being disposed in spaced relation to the ends of the corner members providing a closure receiving recess between them, an end closure member comprising end crosspieces adapted to be received within said recesses and having longitudinal grooves in their outer faces, the corner members having grooves at their ends, and bail-like end closure retaining members of springable material disposed with their bights in said grooves in said end closure crosspieces and engaging the grooves at the ends of the corner members, the arms of the retaining members having inturned lugs engageable in holes in said corner members.
15. In a receptacle, the combination of a frame comprising corner members and side pieces extending between the corner members, one opposed pair of side pieces being disposed in spaced relation to the ends of the corner members providing a closure receiving recess between them, an end closure member comprising end crosspieces adapted to be received within said recesses and having longitudinal grooves in their outer faces, the corner members having grooves at their ends, and bail-like end closure retaining members of springable material disposed with their bights in said grooves in said end closure crosspieces and engaging the grooves at the ends of the corner members, the arms of the retaining members having inturned lugs engageable in holes in said corner members.

JEROME J. HAMLIN.
